UNITED STATES PATENT OFFICE

JOHN SHARP, OF CLEVELAND, OHIO

ELECTROMAGNETIC MASSAGER

Application filed May 5, 1930. Serial No. 449,977.

The invention relates to improvements in electromagnetic massagers for treating the more sensitive or delicate parts of the body such as the eyeballs, throat, solar plexus or 5 ear, &c, which can not be treated with a violent movement.

And the particular features of novelty and utility in the invention are found in the means for producing a gentle magnetic vibration, which will not injure the most delicate membranes.

To accomplish these and other useful results the invention comprises the combination and arrangement of parts and construction of details hereinafter described, illustrated in the accompanying drawings and specifically pointed out in the claims.

In the accompanying drawings, Fig. 1 is a longitudinal section of the device adapted 20 for use with either direct or alternating current; Fig. 2 is a plan of the switch mechanism; Figs. 3 and 4 are plan and elevation of the vibrating disc and massage cup actuated thereby; Fig. 5 is a longitudinal section of a 25 similar device in which the magnetic action is adapted for the use of an alternating or interrupted current; Fig. 6 is a plan of the switch mechanism therefor; Fig. 7 shows a modified form of diaphragm; Fig. 8 is a vertical section of T-headed core taken at right angles to the plane of Fig. 5; Fig. 9 is a plan 30 of a device showing the handle arranged at right angles to the axis of the magnet; Fig. 10 is a longitudinal section thereof; Figs. 11 35 and 12 are edge view and plan respectively of a sanitary shield for the vibrating member; Figs. 13 and 14 are plan and elevation of a vibrating member shaped like a ball and a shield therefor; Figs. 15 and 16 are plan 40 and side elevation respectively of a laminated form of vibrating disc.

In these views A is an electromagnet composed of an iron laminated core wound with the coil of fine wire B, upon the tubular insulation T.

This electromagnet operates to vibrate rapidly the metal disc C which is attached to the armature D to which in turn is attached the massage cup or member E.

50 The core and coil are enclosed in a housing

F and the contact terminals of the coil B are mounted upon a block of insulation G, and a control switch lever H' pivoted at H² in a lining I, is employed to open and close the circuit through the magnet through contact 55 J and K.

In Figs. 1 and 2 the switch mechanism is shown to be provided with a resilient current interrupting and reciprocating member M in addition to the usual contacts J and K by means of which a direct current can be broken into short and rapid impulses to vibrate the disc C.

This member comprises the iron pin M which passes into contact with the core when the core is energized by the passage of electric current therethrough, but is instantly withdrawn by its spring connection J when the contacts are released by the action of the lever.

This lever in Fig. 2 has three positions when in the central position it is adapted for the passage of a direct current. When in the upper position shown in dotted lines it is in position for the passage of an alternating or pulsating current, and when in the lower position it opens the switch contacts.

In Fig. 5 a T-headed sheet metal or laminated core A' is shown wound with the fine wire coil B' and having an external metal shell L which forms the return circuit for the magnetic flow.

In Fig. 5 the armature extends upward towards the core at D² thus being positioned nearer the coil and obtaining a more powerful magnetic effect.

In both figures the core is enclosed in a spool having heads G and G' connected by means of the tubular insulation T.

In Fig. 8 the T-head of the core is enclosed in a metal cup O which makes contact with both the core A' and the outer shell L thus completing the return magnetic circuit.

An insulation P closes the outer end of the unit which is attached by means of screws Q (shown in Fig. 8) to the metal cup. The terminals R and S are attached to a projection of this insulating block.

100 In Fig. 6 the switch lever H' operates in

two positions only and is shown with the switch members U, W, in closed position.

In Figs. 3 and 7, the disc is shown to be provided with openings X to permit of air circulation to secure coolness.

In Figs. 9 and 10 a modified form of Fig. 5 is shown in which the handle Y is placed at right angles to the casing.

In Figs. 11 and 12, 13 and 14 a sanitary attachment Z is shown that can be snapped over the vibratable member, and can be thrown away after use to prevent infection of subsequent patients.

In Figs. 15 and 16, a laminated form of disc is employed, by means of which an accumulated magnetic effect is obtained and a quicker reaction, A.

In this manner a massage instrument is provided that can be used without injury 20. upon the most sensitive tissues with the maximum amount of efficiency at a very low initial cost.

In Figs. 17 and 18, a side elevation and plan are shown of a modified form of disc 25. and sleeve, in which the edges of the disc are cut away at X' and are inserted in corresponding recesses L' in the sleeve L.

This provides narrow openings X for air circulation, and locks the disc in the sleeve 30. so that the vibration of the disc will pump the air about the end of the core and spool and tend to prevent overheating the coil.

Also the vibration of the disc will be much facilitated by cutting away the edges.

35. The construction is also very greatly simplified and made more practical and economical since there are no links, pins, bearings or coiled springs employed that could work loose or get out of order.

40. In Fig. 10 the massage member is found in two sections permitting the outer portion to be exchanged more easily for another.

I claim:

45. 1. In an electromagnetic massaging device, the combination with an electromagnet having a coil and a laminated core therefor, an enclosing cylindrical magnetic shell in contact at its inner end with said core, a disc shaped armature secured to the outer end of said shell, an insulation upon one end of said shell spring contacts thereon for said coil and a switch lever therefor pivoted adjacent to said end of said shell.

50. 2. In an electromagnetic massage instrument in combination, a magnet comprising a coil, a laminated central core therefor, and an external iron cylinder enclosing said coil and core, and in magnetic contact with the inner end of said core and comprising an external return magnetic circuit, and a vibratable iron disc having its edges attached to the outer end of said iron cylinder and a massage cup attached to said disc.

55. 3. In an electromagnetic massage instrument in combination, a magnet comprising

a coil, a laminated central core therefor, and an external iron cylinder enclosing said coil and core, and in magnetic contact with the inner end of said core and comprising an external return magnetic circuit, and a vibratable iron disc having its edges attached to the outer end of said iron cylinder and a massage cup attached to said disc, an external casing, and clamp means on said casing for securing the edges of said disc upon the extremity of said iron cylinder.

4. In an electromagnetic massage instrument in combination, a magnet comprising a coil, a laminated central core therefor, and an external iron cylinder enclosing said coil and core, and in magnetic contact with the inner end of said core and comprising an external return magnetic circuit, and a vibratable iron disc having its edges attached to the outer end of said iron cylinder and a massage cup attached to said disc, the outer edge of said iron cylinder being provided with spaced radial recesses and the outer edge of said iron disc being provided with complementary radial projections, there being openings for air circulation provided between said disc and iron cylinders.

In testimony whereof I affix my signature.
JOHN SHARP.
